[57] **CLAIM**

The ornamental design for a battery for a portable communication device, as shown and described.

DESCRIPTION

FIG. 1 is a top plan view of a battery for a portable communication device, showing one embodiment of our new design;

FIG. 2 is a front elevational view;

FIG. 3 is a bottom plan view;

FIG. 4 is a rear elevational view;

FIG. 5 is a right side elevational view;

FIG. 6 is a left side elevational view;

FIG. 7 is a front, top, and left side perspective view;

FIG. 8 is a rear, bottom, and lower right perspective view;

FIG. 9 is a top plan view of a battery for a portable communication device, showing another embodiment of our new design;

FIG. 10 is a bottom plan view;

FIG. 11 is a right side elevational view;

FIG. 12 is a left side elevational view;

FIG. 13 is a rear elevational view;

FIG. 14 is a front elevational view;

FIG. 15 is a front, top, and left side perspective view; and,

FIG. 16 is a rear, bottom, and lower right perspective view.

The broken line showing in FIGS. 2, 7, 14 and 15 is included for the purpose of illustrating environmental elements only and forms no part of the claimed design.
